ELECTRIC POWERED JUICER

Alfred W. Madl, Milwaukee, Wis., assignor to John Oster
Manufacturing Co., Milwaukee, Wis., a corporation of
Wisconsin

Application June 13, 1956, Serial No. 41,888

Term of patent 14 years

(Cl. D89—1)

Fig. 1.

Des. 179,948

PAGE 2

Fig. 2.

Des. 179,948

PAGE 3

Fig. 3.

Figure 1 is a perspective view of an electric powered juicer embodying my new design, viewing the same from the top, front, and one side thereof;

Figure 2 is a front perspective view, substantially at eye level;

Figure 3 is a perspective view from one side, substantially at eye level; and

Figure 4 is a top plan view.

The dominant features of my design reside in those portions thereof shown in full lines.

I claim:

The ornamental design for an electric powered juicer, as shown and described.
